(57) **CLAIM**

The ornamental design for a display screen with an animated graphical user interface, as shown and described.

DESCRIPTION

FIG. 1 is a first image in a sequence for a display screen with an animated graphical user interface;

FIG. 2 is second image thereof;

FIG. 3 is a third image thereof;

FIG. 4 is a fourth image thereof; and,

FIG. 5 is fifth image thereof.

The appearance of the image transitions sequentially between the images shown in FIGS. 1-5. The process or period in which an image transitions to another forms no part of the claimed design. The outermost broken line in the Figures illustrates a display screen and forms no part of the claimed design. The remainder of the broken lines illustrate portions of the animated graphical user interface that form no part of the claimed design.
